ABRAHAM GOODMAN AND JACOB GOODMAN, OF BROOKLYN, NEW YORK

HAIR-WAVING DEVICE

Application filed April 22, 1929. Serial No. 357,021.

This invention relates to improvements in hair waving devices of the clasp type.

The object of the invention is to provide a simple, efficient and easily operated device to produce a wave of the kind commonly known as a "finger wave".

At present the service of a skilled operator is required to produce such a wave, which is formed by inserting the forefinger of one hand under a lock of hair, to raise the hair into a ridge, then pressing the forefinger of the other hand tightly against it to grip the hair firmly between the two fingers, and finally manipulating the fingers to produce 15 the desired wave.

Our invention provides means for simulating this operation and manipulation mechanically, and enables a woman to produce a "finger wave" in her own hair. The device 20 may be used either on long or short hair.

The invention, broadly considered, comprises a clasp adapted to be fastened to and retained in the hair to form a ridge or vertical undulation therein, and a toothed member 25 slidable longitudinally on the clasp to form a lateral undulation on one side of the ridge. The combined vertical and lateral undulations give the hair a wavy effect which closely simulates that of a "finger wave".

30 Other and further objects of the improvements will appear from the following description thereof, reference being had to the accompanying drawings, in which:—

Figure 1 is a side view of the device with 35 the clasp unfastened and in position to be inserted in the hair.

Fig. 2 is a side view thereof with the clasp closed and the toothed member moved longitudinally thereon;

Fig. 3 is an end view on an enlarged scale; Fig. 4 is an enlarged section on the line 4-4 of Fig. 2;

Fig. 5 is an enlarged section through the pivot on the line 5-5 of Fig. 2; and,

Fig. 6 is a sectional view, similar to that shown in Fig. 4, with a lock of hair engaged in the clasp.

The hair waving device comprises a clasp, indicated generally by the reference character 1, which clasp is curved or arched in the

direction of length to conform substantially to the curvature of the head. The clasp may be made of any suitable material, preferably, because of its lightness and cheapness, of a strip of aluminum, and is provided with two 55 parallel spaced portions 2 and 3.

An arcuate comb 4, also preferably made of the same material, is slidably mounted for longitudinal movement on the clasp. The comb is formed with teeth 5 along its lower 60 edge, and in the embodiment illustrated in the drawings has hooks 6 on its back, which hooks may be formed by stamping them from the material of which the comb is made. The hooks engage and ride in slots 7 cut in the 65 side portion 2 of the clasp. This provides a simple means of slidably securing the comb to the clasp, but, obviously, any other suitable construction may be used. A handle 8 is formed at one end of the comb for convenience 70 in sliding the comb. The handle may be made by bending up an end portion of the comb as seen in Fig. 3.

Teeth 9 may be stamped or cut in the lower edge of the portion 3 of the clasp. These 75 teeth, however, do not perform any essential function in the hair waving operation, but merely assist in retaining the device in the hair, and may therefore be omitted if desired.

A curved bar or tongue 10 is pivoted at 80 11 to one end of the clasp and extends the full length thereof, between the side portions 2 and 3, with its free end 12 projecting beyond the clasp to provide a handle. The 85 bar in closed position extends or lies in a plane above the base or root of the teeth 5 of the comb, and close to the side portion 3 of the clasp, as shown in Figs. 2 and 4 of the drawings. A suitable catch 13 is provided to engage and hold the free end of the bar in its closed position. The catch may be formed integral with the clasp by stamping it out of the portion 3 at the end opposite to that to which the bar is pivoted.

In operation, the bar 10 is inserted under hair at the place where the wave is to be formed, the hair being preferably wet or damp, and then the clasp is closed down over the bar, and the free end of the latter is en-

gaged in the catch to hold the device in the hair. This raises the hair from the scalp and forms a ridge or vertical undulation therein as indicated in Fig. 6. The hairs at one side of the ridge are firmly gripped and held immovable between the bar 10 and the side portion 3 of the clasp, while the hairs at the opposite side of the ridge are engaged between the teeth 5 of the comb and are free to move on movement of the comb 4. The comb is then slid longitudinally from its initial position shown in Fig. 1 to an adjusted position as shown in Fig. 2. This shifts the hairs laterally on the free side of the ridge and forms a wave therein, which lateral wave, combined with the vertical wave formed by clasping the hairs over the bar 10, produces a wave of double curvature simulating the effect of a finger wave. It will be seen, upon referring again to Fig. 6, that the crest of the vertical wave, that is the portion of hair lying on top of the bar 10, is held relatively fixed at a point higher than the base of the teeth 5 of the comb, and consequently the sliding movement of the comb will not appreciably flatten or draw out said wave. After the device has been thus fastened and adjusted in the hair it is permitted to remain until the wave has set, when it may be removed by unfastening the bar from its catch, raising the clamp, and slipping the bar out from under the wave.

Various modifications in the construction and arrangement of parts herein illustrated and described may be made without departing from the scope of the invention.

What we claim is:—

1. A hair waving device comprising a clasp having two spaced parallel side portions, a comb slidably supported on one of said portions for longitudinal movement, a bar pivoted at one end to the clasp intermediate its side portions and extending lengthwise thereof, and a catch on the clasp to hold the free end of the bar in closed position.

2. A hair waving device comprising a clasp having two spaced parallel side portions, one of said portions having a toothed lower edge, a comb slidably supported on the other of said portions for longitudinal movement, a bar pivoted at one end to the clasp intermediate said portions and extending lengthwise thereof above the plane of the base of the comb-teeth, and a catch on the clasp to hold the free end of the bar in closed position.

3. A hair waving device comprising a clasp having two spaced parallel side portions, a comb integral with one of said side portions, and a second comb slidably mounted on said clasp in juxtaposition to the other of said parallel side portions.

4. A hair waving device comprising a U-shaped clasp having two parallel side portions, one of said side portions being of rela-

tively greater height than the other and serrated to form a comb, and a second comb slidably mounted on said clasp in juxtaposition to the other of said parallel side portions.

5. A hair waving device comprising a clasp having a side portion serrated to form an integral comb, a bar pivoted at one end of said comb portion for securing said bar in position, and a second comb mounted on said clasp and adapted for longitudinal movement relatively to said first comb.
